UNITED STATES PATENT OFFICE.

AUGUST ROCHWITE, OF GREEN LAKE, WISCONSIN, ASSIGNOR OF ONE-THIRD TO
HALBERT W. BROOKS, OF GREEN LAKE, WISCONSIN.

BOTTLE-STOPPER.

1,074,293.

Specification of Letters Patent. Patented Sept. 30, 1913.

Application filed April 23, 1913. Serial No. 763,094.

To all whom it may concern:

Be it known that I, AUGUST ROCHWITE, a citizen of the United States, residing at Green Lake, in the county of Green Lake and State of Wisconsin, have invented certain new and useful Improvements in Bottle-Stoppers; and I do hereby declare the following to be a full, clear, and exact description of the invention, such as will enable others skilled in the art to which it appertains to make and use the same.

This invention relates to new and useful improvements in bottle stoppers, and has for its object to provide a disk stopper which may be easily and quickly removed from its position in a bottle.

Another object of my invention is to provide a device of the above character which will permit the removal of such stoppers without the necessity of inserting a sharp instrument or the like into the stopper.

A still further object of my invention is to provide a bottle stopper which may be easily removed and at no time will the operator's hands or fingers come in contact with the contents of the bottle.

With the above and other objects in view, I will now proceed to describe my invention in the following specification and accompanying drawings, in which,

Figure 1 is a sectional view of a fragment of a bottle, showing my improved stopper in place and in position to be removed; Fig. 2 is a top plan view of my improved bottle stopper; and Fig. 3 is an edge view of my improved bottle stopper.

Referring to the drawings by characters of reference, 5 indicates the usual neck of a milk bottle, having formed at its upper extremity the usual bead 6 and the shoulder 7, against which the edge of the stopper is adapted to seat.

My improved bottle stopper preferably comprises the body portion 8, having adjacent one side the curved slits 9. These curved slits are adapted to form a tongue 10, which extends inwardly toward the center of the bottle stopper and connects with the body portion 8 near the outer periphery of said body portion, so that when the inner end of the tongue is pressed downwardly the weakened portions 11, caused by the slits coming near the periphery will bend, as is clearly illustrated in Fig. 1, and the por-

tion of the stopper intermediate the outer extremity of the tongue and the periphery of the body portion will bend upwardly and permit the thumb of the operator to be inserted therein.

In order to provide a means whereby the bottle stopper may be inserted without becoming bent, as shown in Fig. 1, I preferably provide a ligament 12, which connects the inner extremity of the tongue with the body portion 8 of the bottle stopper, as is clearly illustrated in Fig. 2.

In placing my improved bottle stopper in position, it is forced inwardly in the same manner as those in use at the present time, but when it is desired to remove said stopper the ligament 12 is broken and the end of the tongue 10 pressed downwardly, which will cause the portion 11 intermediate the tongue 10 and the periphery of the body portion 8 to bend which will cause the portion intermediate the outer extremity of the tongue 10 and the periphery of the body portion to rise, thus permitting the operator to insert the point of his thumb between the bead 6 on the bottle and the raised portion of the bottle stopper, and it will be seen that at no time does the operator's hand come in contact with the contents of the bottle so that at all times sanitation is insured.

While in the foregoing I have shown and described the preferred embodiment of my invention, I wish it to be understood that I may change the specific arrangements of parts without in any way departing from the spirit and scope of my invention.

Having fully described my invention, what I claim is:

1. A bottle stopper comprising a circular body portion, said circular body portion having segmental slits adjacent its edge, an inwardly extending tongue formed intermediate the slits, said inwardly extending tongue being adapted to be pressed downwardly whereby the portion intermediate the tongue and the periphery of the body portion will be bent upwardly.

2. A bottle stopper comprising a circular body portion, said circular body portion having segmental slits adjacent its periphery and to one side of the center, a tongue intermediate the slits, a ligament formed on the end of the tongue and connecting said

tongue with the body portion, a weakened portion formed intermediate the outer extremity of the tongue and the periphery of the body portion, said weakened portion being adapted to bend and cause the portion intermediate the outer extremity of the tongue and the periphery to rise upwardly, thereby permitting the insertion of the

thumb of the operator between the stopper and the bead on the bottle neck.

10

In testimony whereof I affix my signature in presence of two witnesses.

AUGUST ROCHWITE.
